UNITED STATES PATENT OFFICE.

FREDERICK P. JARRETT, OF GALENA, KANSAS.

TWINE-HOLDER.

SPECIFICATION forming part of Letters Patent No. 743,643, dated November 10, 1903.

Application filed March 17, 1903. Serial No. 148,263. (No model.)

To all whom it may concern:

Be it known that I, FREDERICK P. JARRETT, a citizen of the United States, residing at Galena, in the county of Cherokee and State of Kansas, have invented certain new and useful Improvements in Twine-Holders, of which the following is a specification.

My invention relates to devices for holding twine used in shops and stores for tying packages of merchandise, and has for one of its objects to provide a device to be suspended from the ceiling, in which a multiplicity of strands of twine may be mounted.

Another object of my invention is to provide means by which either cones or balls of twine may be used to the exclusion of the other or both used at one time.

Another object of my invention is to provide a weighted take-up to raise the free end 20 of the cord out of the way when not in use.

A further object of my invention is to provide a twine-guide that is vertically adjustable, so that the end of the twine may be raised to any height desired when not in use.

I also provide a spring-clip on the twine-guide for holding pictures, advertising matter, &c., if desired, to give an ornamental appearance to the device.

The construction and operation of my invention will more fully appear hereinafter and by reference to the accompanying drawings, in which—

Figure 1 is a front view in elevation of my improved twine-holder in which a single cone and ball of twine are in use; Fig. 2, a front view, partly in section, of a holder for two cones and two balls; Fig. 3, a front view of a holder for four cones and four balls; Fig. 4, a top plan view of holder shown in Fig. 3, and Fig. 5 a detail view of ball-cup used with the holder shown in Figs. 3 and 4.

Referring to the drawings, in which similar reference characters indicate corresponding parts throughout the several views, A 45 represents the base-piece of my device, on which is secured the upright frame B, having the angular apex C to hang the device from a hook in the ceiling or other suitable support.

The base A in Figs. 1 and 2 consists of a single bar having, as shown in Fig. 1, a single frustum-shaped projection D, secured on

its upper side to support a cone of twine E and a ball-cup F to its lower side to hold a ball of twine G. The ball-cup consists, preferably, of a hemispherical shell H, secured to the base A, and another hemispherical shell I, hinged to H at K and held in a closed position by means of spring-clasp L.

In Fig. 2 two frustum-shaped projections D are shown, and two cups F may be employed, though I prefer to use a single cup, larger in diameter, having a partition therein to provide compartments for two balls.

In Fig. 3 the base A consists of two pieces 65 joined at their centers at right angles to one another, forming a cross M, on each arm of which is secured one of the projections D, while the ball-cup F is made with four compartments, as shown in Fig. 5, to receive four 70 balls of twine.

N represents the twine-guide, which is slidably mounted on the frame B and has the eyelets O secured thereto, through which the twine runs. It will be noted that frame B is 75 wider at the bottom than at the top, and as the rod N is slidably mounted on frame B it is held in any desired position by frictional contact therewith.

P represents a take-up weight 80 slidably mounted on each side of the frame B between the base A and guide N, having an eyelet Q, through which the twine is threaded from one of the eyelets O on the guide N and then carried back and threaded through another eyelet O at the end of the guide. The purpose of this take-up is to draw the free end of the string up out of the way when not in use, and by regulating the height of the guide N relative to the base A it will readily appear that the 90 height to which the end of the twine may be raised can be regulated as the operator wishes.

In Figs. 3 and 4 the frame B is connected to two opposite arms of the cross-shaped base M, while two upright rods R extend upward 95 from the other two arms. The twine-guide consists of two bars, one slidably mounted on the frame B, the other on the rods R, and may be joined at their centers or not, as desired. Take-ups P are also provided on the 100 rods R as well as the sides of frame B. In the structure shown in Figs. 2, 3, and 4 two strands of twine are connected with each take-up, as shown.

S represents a spring-clip secured to the guide N to hold an advertising card or picture J between it and the frame B.

Having thus described my invention, what I claim is—

1. In a twine-holder, a base, an open frame secured thereto, take-up weights mounted on said frame, and a twine-guide vertically adjustable on said open frame to regulate the length of twine taken up, substantially as shown and described.

2. In a twine-holder, a base, an open frame secured thereto, twine-holders secured to said base, a twine-guide vertically adjustable on said frame, eyelets secured to said guide through which the twine is threaded, and take-up weights slidably mounted on said frame, substantially as shown and described.

3. In a twine-holder, a base, frustum-shaped projections extending upwardly therefrom to receive twine cones, a ball-twine cup secured below said base, a frame secured to said base having an angular apex to suspend the device, a twine-guide slidably mounted on said

frame, eyelets secured to said guide through which twine is threaded, and take-up weights slidably mounted on said frame between the base and guide having eyelets through which the twine is threaded between two of the eyelets on the guide, substantially as shown and described.

4. In a twine-holder, a base, twine-cone supports secured thereto, a ball-twine cup secured below said base having as many compartments therein as there are cone-supports secured to the base, a frame secured to the base wider at the base than at the top, a twine-guide adjustably mounted on said frame, and take-up weights slidably mounted on said frame between the base and guide, substantially as shown and described.

In testimony whereof I hereto affix my signature in the presence of two witnesses.

FREDERICK P. JARRETT.
